DESIGN FOR AN INSTRUMENT CASING

Frederick W. Side, Philadelphia, and Thomas R. Harrison, Wyncote, Pa., assignors to The Brown Instrument Company, Philadelphia, Pa., a corporation of Pennsylvania

Application October 11, 1934, Serial No. 53,586

Term of patent 14 years

To all whom it may concern:

Be it known that we, Frederick W. Side, a citizen of the United States, residing at 1832 Albanus Street, Philadelphia, in the county of Philadelphia and State of Pennsylvania, and Thomas R. Harrison, a citizen of the United States, residing at 140 Hewitt Road, Wyncote, in the county of Montgomery and State of Pennsylvania, have invented a new, original, and ornamental Design for an Instrument Casing, of which the following is a specification, reference being had to the accompanying drawing, constituting a part hereof:

Fig. 1 is a front elevational view of our instrument casing, and

Fig. 2 is a side elevational view of our instrument casing as viewed from the right of Fig. 1.

We claim:

The ornamental design for an instrument casing substantially as shown.

In testimony whereof, we have hereunto subscribed our names this 9th day of October 1934.

FREDERICK W. SIDE.
THOMAS R. HARRISON.
